UNITED STATES PATENT OFFICE.

ISADORE KAUFMANN, OF HOBOKEN, NEW JERSEY, ASSIGNOR TO WILLIAM LUTTER,
OF NEW YORK, N. Y.

SAFETY-RAZOR.

1,076,375.

Specification of Letters Patent. Patented Oct. 21, 1913.

Application filed July 22, 1912. Serial No. 718,917.

To all whom it may concern:

Be it known that I, ISADORE KAUFMANN, a citizen of the United States, residing at Hoboken, in the county of Hudson and State of New Jersey, have invented certain new and useful Improvements in Safety-Razors; and I do hereby declare the following to be a full, clear, and exact description of the invention, such as will enable others skilled in the art to which it app pertains to make and use the same.

This invention relates to safety razors and has for an object to provide a razor in which the greatest number of cutting edges are possible.

An object of this invention is to provide a device to hold a number of blades and which blades are adjustable or variable in a holder so that each of the four edges of each blade may be brought into cutting relation with respect to the holder.

A further object of this invention is to provide a device capable of using elongated rectangular blades of reduced size which blades may be fitted on the holder so that one of the long edges of all four blades are exposed for cutting and the ends of two of the blades are exposed to coöperate with the long edges of the other two blades.

A further object of this invention is a provision of means for conveniently holding the above-mentioned elongated blades in such a way that the blades may be easily applied and removed for rearrangement.

Further objects will be apparent from the following specification, appended claims and drawings, in which—

Figure 1 is a plan view of one of the blades used in connection with this device, Fig. 2 is a plan view of the guard member with four blades positioned thereon, Fig. 3 is a bottom view of the upper member which coöperates with the guard member in holding the blades in position, and Fig. 4 is a sectional view of the razor as on the line 4—4 of Fig. 3.

Referring to the drawings, 10 indicates a blade having the elongated opening 11 therein and also having each of the four edges sharpened as at 12. The guard comprises a plate 13 having the edge thereof notched as at 14 and said guard being provided with the elongated openings 15 to correspond with the openings 11 in the blade and which openings are so positioned as to

cause the blades secured to the guard to assume the position shown in Fig. 2 in which an elongated edge of each of the blades is exposed for cutting and the ends of the end blades are in alinement with the cutting edge of the side blades and which blades are interchangeable with respect to the guard so as to permit all of the edges to be used for cutting purposes in their turn.

Coöperating with the guard 13 is the plate 16 having the lugs 17 depressed therefrom and a threaded stem 18 depending from the middle thereof, the elongated lugs 17 being adapted to pass through the opening 11 of the blades 10 and the opening 15 of the plate 13 when the device is assembled and the lug or stem 18 is adapted to pass through the opening 19 in the plate 13 and to engage the threaded socket 20 of the handle 21. The handle 21 has a flaring shoulder 22 at the upper end thereof and the threaded socket 23 in the lower end which socket is adapted to receive the threaded stem 24 carried by the handle portion 25.

As this device is extremely simple in its operation it is apparent from the foregoing as to the operation and adjustment of the several parts and I am aware that various modifications may be made within the scope of my invention and the drawings have been submitted for illustrative purposes only.

Having thus described my invention, I claim:

1. In a safety razor, a rectangular guard having each of its edges notched, elongated slots adjacent to and parallel with the central portion of each of said edges, a rectangular clamping plate having elongated lugs formed thereon to register with the slots in the guard plate, a threaded stem depending from said clamping plate to receive a handle in combination with a rectangular cutting edge comprising a set of small rectangular, interchangeable and reversible blades having each of their four edges sharpened to a cutting edge and arranged so that one long edge of each of the blades is exposed and the short edges of two of the blades are in alinement with and form a continuation of the long cutting edge of the other two blades.
2. In a safety razor, a rectangular cutting member composed of a set of smaller revers-

ible, elongated blades having each of their four edges sharpened, the ends of two of said blades contacting with the sides of two other blades to present a continuous rectangular cutting edge.

3. In a safety razor, a rectangular cutting member formed of a set of reversible elongated blades having each of their four edges sharpened, said blades being assembled by 10 having one long edge of all the blades ex-

posed and the ends of two of said blades exposed, the adjacent short ends and elongated edges presenting a continuous edge.

In testimony whereof I affix my signature in presence of two witnesses.

ISADORE KAUFMANN.
